(57) **CLAIM**

The ornamental design for an information handling system keyboard, as shown and described.

DESCRIPTION

FIG. 1 is a front perspective view of the information handling system keyboard comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; and, FIG. 8 is a front perspective view thereof having a palm rest installed.

Broken lines shown in the drawings illustrate portions of the information handling system keyboard, and form no part of the claimed design.
